FIG. 2 - 11

FIG. 1 is a front elevational view of a knock-down exhibitor embodying our new design;

FIG. 2 is a side elevational view thereof;

FIG. 3 is a rear elevational view thereof;

FIG. 4 is a top plan view of the table portion thereof, the top portion being omitted for convenience of illustration;

FIG. 5 is a bottom plan view of the table portion thereof, the support legs being omitted for convenience of illustration;

FIG. 6 is a cross-sectional view thereof taken on line 6—6 of FIG. 1;

FIG. 7 is a fragmentary cross-sectional view thereof taken on line 7—7 of FIG. 4;

FIG. 8 is a top plan view of the top portion thereof, the lower portion being omitted for convenience of illustration;

FIG. 9 is a rear elevational view of the table portion thereof, the top portion and the legs being omitted for convenience of illustration;

FIG. 10 is a front elevational view of a modified form

of the knock-down exhibitor shown in FIGS. 1 through 9;

FIG. 11 is a side elevational view of FIG. 10;

FIG. 12 is a top plan view of FIG. 10; and

FIG. 13 is a rear elevational view of FIG. 10.

It is to be understood that the fragmentary showing of apertures in FIGS. 1, 2, 3, 10, 11 and 13 are continuous throughout the panels in which they appear.

The broken line representation of letters in FIGS. 1 and 10 are for illustrative purposes only.

We claim:

The ornamental design for a knock down exhibitor, substantially as shown and described.
